UNITED STATES PATENT OFFICE.

JAMES MCQUEEN, OF CLIFTON, NEW JERSEY.

ROOF.

Application filed November 18, 1921. Serial No. 516,011.

To all whom it may concern:

Be it known that I, JAMES MCQUEEN, a citizen of the United States, residing at Clifton, in the county of Passaic and State 5 of New Jersey, have invented a certain new and useful Improvement in Roofs, of which the following is a specification.

The invention relates to sheet metal roofs and is designed particularly for the roofs of 10 railway freight cars and like structures.

The object of the invention is to provide a roof of sheet metal, economically constructed and easily applied, which shall be eminently strong and durable and in which the 15 danger of leaks is avoided.

Another important object is to provide a form of joint for the roof sections which shall avoid the use of solder and be leak proof.

20 A further object is to provide means for securing the roof sections reliably to the car-lines or roof frame, and for joining the running board saddles to the sections and car-lines without puncturing the roof for the 25 reception of bolts or like fastenings.

Another important object is to provide means for sealing effectually the ends of the roof-joints and for protecting the nails or other fastening means by which the valance 30 or depending flanges of the sheet metal is secured to the fascia boards at the sides and ends of the car.

The invention consists in certain novel features and details of construction and arrangement by which the above objects are attained, to be hereinafter described and claimed.

40 The accompanying drawings form a part of this specification and show an approved form of the invention as applied to a freight car.

Figure 1 is a plan view of the improved roof at one end of the car, partially broken away and in horizontal section.

45 Figure 2 is a corresponding side elevation, partly in vertical section.

Figure 3 is an end view of the roof portion of the car.

50 Figure 4 is a corresponding transverse section, partly in elevation.

The remaining figures are on a larger scale.

Figure 5 is a transverse section through the margins of two adjacent sheets of metal 55 to be joined, showing the manner of forming the joint.

Figure 6 is a similar section showing three completed joints.

Figure 7 is an elevation showing a "button" or means of fastening the valance of 60 the roof to the fascia boards.

Figure 8 is a similar view of a portion of the valance before the application of the button.

Figure 9 is a horizontal section taken on 65 the line 9—9 in Figure 7.

Figure 10 is a transverse section through one of the car-lines and a roof joint, showing the means for securing the roof to the car-lines. 70

Fig. 11 is a transverse section through one of the running-board saddles and a roof joint, showing the means for fastening the saddle to the roof.

Figure 12 is a vertical section correspond- 75 ing to the preceding figure.

Figures 13, 14 and 15 are elevations showing progressive steps in sealing the ends of the roof joints.

Figure 16 is a plan or top view corre- 80 sponding to Figure 15.

Figure 17 is an elevation corresponding to Figures 13, 14 and 15, showing the seal completed.

Figure 18 is a plan or top view corre- 85 sponding to Figure 17.

Similar reference numerals indicate the same parts in all the figures.

Referring to the drawings, 20 is the ridge pole of the car, and 21 the purlins or longitudinally extending roof-beams, and 22 are the car-lines or transverse rafters, 23 the runningboard, and 24 the runningboard 90 saddles.

The roof is composed of wide strips of 95 sheet metal 25 extending transversely of the car and joined at their adjacent margins, with their ends overlapped upon the sides and ends of the car in a narrow depending flange or valance 26.

The joint between adjoining sheets or roof-sections is formed by bending or folding the margins as shown in Figures 5 and 105 6, in which the margins of one section are bent upwardly at a right angle as at 27, then downwardly at 28, and thence again upwardly as a vertical flange 30 and forming a channel 29. The margins of the next sections are bent upwardly at 31 and then downwardly at 32 to form the interior channel 33, and terminating in the depending vertical flange 34. In applying the sections 110

together the sheet bearing the upwardly extended flanges 30 is laid in place on the carlines and an adjacent section bearing the depending flange 34 is lowered with such flange received in the channel 29, and receiving the fold 27 and 28 in its channel 33. The flange 30 is then folded over and down as at 41 to inclose completely the portions 31 and 32 of such adjacent sheet or section and 10 lock the sections firmly together. The next adjacent section is similarly joined, each alternate section being equipped on both margins with the vertical flanges 30, and the intermediate sections bearing the down- 15 wardly extended flanges 32. The joints thus constructed may be pinched to bring their parts into close relationship and it will be noted that the entrance of moisture is effectively prevented by the tortuous vertical 20 passages it must follow to reach the under face of the roof. The joint is preferably further protected by paint applied as usual, filling the narrow interstices between the upper surfaces of the sections and the depending portions of the joint. 25

At the ends of the sections the valance 26 lies upon the upper margin of the fascia-board 35 and is nailed thereto as shown in Figures 7, 8 and 9. The valance is cut vertically for a short distance as at 36 and then longitudinally in each direction from the upper end of the cut 36, as at 37 to form wings 38. The holding nails are driven adjacent the notch produced by forming the 35 wings, and the latter are then folded over the nail heads; in the vertical channels 39 thus produced are received the inwardly bent folds of a strip or "button" 40 which covers the notch in the valance and is firmly 40 held in place by flattening the bends by blows of a hammer or otherwise. The side margins of the end sections are similarly secured to the ends of the car as shown in Figure 3.

45 To seal the ends of the joints between the sections against the entrance of moisture, the portions 30 and 41 of one section are extended as flaps 42 and 43, and a tongue 44 of sheet metal is nailed to the fascia-board below the joint, see Figure 13, which is folded upwardly to cover the nail heads and the joint between the flaps, and extends upwardly beyond the joint. The flaps 42 and 43 are then folded upon the tongue, as in 50 Figure 14, the projecting end of the tongue is then folded down upon the flaps as in Figures 15 and 16. The joint-end may be left in this condition but it is preferable to pinch the flaps and tongue together, as shown 55 in Figures 17 and 18, or otherwise close the interstices. Thus closed, moisture is effectively excluded from the ends of the joints without requiring the use of solder. 60

65 The nails at the buttons 40 attach the roof sections securely to the eaves and ends of the

car, and the roof is held to the carlines 22 at intervals by anchors 45 of sheet metal, as shown in Figure 10 in which the folded upper portion 46 is engaged in the joint of the roof sections by inclosing the portions 70 27 and 28 and extending downwardly between the portions 27 and 31, and thence downwardly on one face of the carline, beneath the latter and upwardly on the other face where it is fastened to the carline by 75 nails 47. This mode of fastening avoids the use of bolts or nails extending through the roof.

At the centre of each joint the portion 30 is cut vertically as at 48 to facilitate the 80 slight bend required above the ridge-pole 20 in conforming to the inclines of the car roof, see Figure 12, and two fins 49 are left standing vertically when the portion 41 is folded down in forming the joint as above described. Each runningboard saddle is 85 grooved longitudinally at 50 and is also provided with a slit or saw-kerf 51 extending vertically from such groove. The latter receives the roof-joint, and the fins 49 extend 90 into the saw-kerf; the saddle is secured to the sections by bolts 52 extending transversely through the saddle and fins 49.

95 It will be observed that the car roof thus constructed has no openings leading from the exterior to the interior, and consequently the danger of leaks is eliminated. Soldering is not required, and painting affords all the protection necessary in resisting the action of the elements. The structure is strong and 100 durable and eminently simple and economical.

105 Although the invention is shown and described as applied to freight cars, it will be understood that it may be applied to any structure to which it may be adapted, and that modifications may be made as required in such adaptations.

I claim:—

110 1. In a roof consisting of sections of sheet metal, the joint described comprising on the margin of one section an upwardly extended portion folded downwardly upon itself and thence again upwardly as a vertical flange, forming with such downwardly folded portion 115 an exterior open channel, and the margin of the adjacent section bent upwardly and thence downwardly to form an interior channel, said folds and channels of both sections arranged to interlock and be held by 120 folding said flange downwardly upon the upwardly bent portion of the second mentioned section.

125 2. In a roof consisting of sections of sheet metal having interlocked joints at their margins, vertically extended fins on one of said sections at such joints, runningboard saddles each having a groove adapted to receive one of said joints, and a kerf extending from such groove and adapted to receive said fins, 130

and fastening means extending through said saddle and fins.

3. In a roof consisting of sections of sheet metal having interlocked joints at their margins, a fascia board, oppositely located laterally extended flaps on one of said sections at the end of such joint, and a sheet metal tongue on said fascia board below such joint, said tongue adapted to be folded upwardly and inclosed by folding said flaps thereupon and thence downwardly upon the exterior of said flaps to seal the end of such joint.

4. In a sheet metal roof having a valance extending downwardly upon the structure to be roofed, said valance having a vertical cut and lateral cuts extending oppositely therefrom to form bendable wings, fastening

means extending through said valance and into said structure adjacent said wings and covered by folding said wings outwardly upon said means, and a strip of sheet metal folded inwardly upon itself at its ends, adapted to engage in the folds of said wings and inclose the latter and cover the notch in said valance produced by the folding of said wings.

In testimony that I claim the invention above set forth I affix my signature, in presence of two witnesses.

JAMES McQUEEN.
